Augustus B. Langford

ATTORNEY

UNITED STATES PATENT OFFICE.

ARTHUR MIDDLETON ROSE, OF YONKERS, NEW YORK.

DESIGN FOR CARPET.

SPECIFICATION forming part of Design No. 27,055, dated May 11, 1897.

Application filed April 2, 1897. Serial No. 630,491. Term of patent 3½ years.

To all whom it may concern:

Be it known that I, ARTHUR MIDDLETON ROSE, a citizen of the United States, residing at the city of Yonkers, in the county of West-
5 chester and State of New York, have invented and produced a new and original Design for a Carpet or other Fabric, of which the following is a specification, reference being had more particularly to the accompanying drawing,
10 illustrating the same and forming part hereof.

The leading feature of my design comprises a chintz pattern of delicate scrolls and floral ornaments displayed upon a plain ground.

In the drawing, *a* is the body, *b* the border, and *a b* the complete carpet.
15 *c* are delicate scrolls. *d* are the floral ornaments, and *e* is the ground, upon which said scrolls or ornaments appear arranged as a chintz pattern.

20 This design is adapted for use as a six-frame

chintz pattern. However, it will be best understood by reference to the accompanying drawing, and it may be expressed in different colors or combinations of colors and applied to velvet, Wilton, Brussels, ingrain, 25 and other carpets.

What I claim as my invention, and desire to secure by Letters Patent, is—

1. In a design for a carpet, the body *a*, substantially as shown.
2. In a design for a carpet, the border *b*, substantially as shown.
3. The design for a carpet consisting of the body *a*, and border *b*, substantially as shown.

In testimony whereof I have hereunto 35 signed my name.

ARTHUR MIDDLETON ROSE.

In presence of—

N. A. McMANUS,
W. J. JACKSON.
